APPARATUS FOR THE CONVERSION OF
ENERGY IN A FLOWING STREAM OF
FLUIDSWalter Squires, Jr., Westfield, N. J., assignor to
Standard Oil Development Company, a corpo-
ration of Delaware

Application October 7, 1948, Serial No. 53,342

1 Claim. (Cl. 103—43)

1
The present invention relates to apparatus for the conversion of energy in a flowing stream of fluids. More particularly, it relates to the use of a multi-stage centrifugal pump as a fluid motor to drive another pump, such as a centrifugal pump.

It is an object of the invention to provide a means whereby in the process of reducing pressure on flowing a stream of a high pressure fluid, the major portion of such stream may be employed to raise the pressure of a minor portion of the stream above that of the stream itself, utilizing the energy released in reducing pressure on the major portion of said stream to drive the multi-stage centrifugal pump as a fluid motor. Another object of the invention is to provide such apparatus in which the need for high pressure seals for a rotating shaft therein, is substantially eliminated.

An example of an operation in which the use of such apparatus is advantageous is found in the manufacture of ethyl alcohol synthetically. In such a process, ethylene is first absorbed in concentrated sulphuric acid, under suitable conditions of temperature and pressure, to form an extract comprising a mixture of mono and diethyl sulphates together with some free acid. A portion of this extract is pumped to the top of an ethylene absorption tower in sufficient quantity to produce, when mixed with a feed acid, a fluid of maximum absorptive capacity with minimum corrosive tendencies. Pressure on the remainder of the extract is then reduced and the extract diluted with water to hydrolyze the ethyl sulphates to alcohol and/or ether. In returning the one portion of the extract to the ethylene absorption tower it is necessary to slightly increase its pressure and the pump used for this step is required to be of special construction in order to avoid the tendency for leakage around the pump shaft, and also to minimize corrosion of parts. The difficulties experienced in an effort to attain such qualifications have been considerable and have not been satisfactorily overcome. By the present invention it is proposed to provide pumping apparatus in which the driving shaft is fully contained within the casing elements and eliminating driving means such as electric motors, particularly subject to the effect of acid leakage such as is normally experienced. At the same time, the apparatus, according to the invention, provides means whereby the energy to be dissipated in reducing pressure on the major portion of the extract may be gainfully employed to operate the pump for recycling the minor portion of the

2
extract. Such apparatus may be employed equally as well in a variety of situations, such as in conjunction with an alkylation process, or any other situation in which the problem of leakage is similarly encountered, or where the reduction of pressure on a process fluid affords an opportunity of utilizing the energy dissipated in such fashion, in the manner set forth.

The invention and its objects may be more fully understood from the following specification when read in conjunction with the accompanying drawing, in which the related elements of the apparatus are shown in side elevation with parts broken away to more clearly illustrate internal construction.

In the drawing, the numeral 1 designates the casing of a multi-stage centrifugal pump and the numeral 2 the casing of a pump, such as a single-stage centrifugal pump, the two pumps having inlets 3 and 4 and outlets 5 and 6, respectively. Preferably, a common base 7 is provided for the pumps 1 and 2, on which they are disposed in longitudinally spaced relation, and substantially concentric one with another, with annular end portions 1a and 2a in opposed relation. A common shaft 8 is provided for the two pumps. This shaft may be a single member or may be formed of two portions joined as by coupling 9. The outer end portions of this shaft are to be entirely contained within the casings 1 and 2. If bearing elements are to be provided for the outer ends of the shaft, these are also to be contained within the casings or within some form of cap structure 8a, sealed with reference to the casing. Between the two casings 1 and 2, is provided a sleeve member 10, the ends of which are secured to and sealed with reference to the end portions 1a and 2a of the respective casings, this sleeve, forming a shaft-way for the shaft 8. As supports for the inner portions of the shaft, bearing members 11 and 12 are provided in the shaft-way 10 and seals 13 and 14 are provided around the shaft where it passes through the respective end portions of the casings. It is to be noted in this connection that only a comparatively small pressure difference will exist between the casing 1 and the casing 2. For example, if the fluid supplied to the inlet 3 of the pump 1 is at a pressure of about 500 pounds per square inch, substantially the same pressure will exist at the inlet 4 of the pump 2, and assuming that a 50 pound increase in pressure is to be applied to the fluid leaving the outlet 6 of pump 2, no more than a 50 pound differential need be provided against by the seal members 13 and 14. If desired, the bearings 11 and 12 may be either

lubricated by the fluid being handled or lubrication may be provided by separate means. If desired, the elements 1 and 2 may be disposed in vertically spaced relation, the construction otherwise remaining substantially the same.

In operation, the fluid material to be handled by the apparatus described, is supplied thereto as by way of conduit 15 having branched connections 15a and 15b of which the former is connected to the inlet 3 and the latter to the inlet 4 of pumps 1 and 2, respectively. Valves 15c and 15d are to be provided in the respective branch lines for the purpose of regulating the supply of fluid from the stream of fluids in line 15 which is introduced into the respective pumps by way of inlets 3 and 4. The operation of the apparatus described may be suitably regulated in known fashion so that the fluid leaving the outlet 5 of pump 1 will be at any desired reduced pressure as compared with the fluid entering the inlet 3. Normally, the reduced pressure will be substantially atmospheric. Likewise, the pressure increase on the fluid portion leaving the outlet 6 of pump 2 may be regulated, but normally this pressure will be in the range required by the operation in which the pump is used and as determined by the construction and physical characteristics of the pump 2.

What is claimed is:

Apparatus for the conversion of energy in a high pressure flowing stream of fluids, comprising a pair of independent units, one unit of said pair consisting of a pump unit and the other unit of said pair consisting of a fluid motor, each unit being enclosed in a casing provided with an inlet and an outlet, said units being disposed in longitudinally spaced, opposed end relation, and hav-

ing the inlet of one unit juxtaposed with reference to that of the other, shafts of said units extending through the opposed ends of the units and a coupling means joining said shafts between the units, the opposite ends of said coupled shafts terminating at points within the said casings, bearings within said casings and sealed in fluid tight relation thereto, said opposite ends of said shafts terminating within said bearings, an annular sleeve element concentric with the shafts extending between the said casings and said sleeve element being detachably fixed to said casings in pressure tight and fluid tight relation thereto, forming a sealed passageway between the casing for the coupled shafts, a shaft seal and bearing support at each end of said sleeve interiorly thereof, conduit means for a stream of high pressure fluid, including a branch connection communicating with each of the casing inlets, and valve control means in each of said branch connections adapted to divert a major portion of said stream through the said fluid motor and a minor portion through said pump unit.
